VEGETABLE DISH.

No. 16,166

14, 1885.

Fig. 1

UNITED STATES PATENT OFFICE.

ALFRED ERNEST HILLS, OF BURSLEM, COUNTY OF STAFFORD, ENGLAND,
ASSIGNOR TO JOHN HALL, OF BOSTON, MASSACHUSETTS.

DESIGN FOR A VEGETABLE-DISH.

SPECIFICATION forming part of Design No. 16,166, dated July 14, 1885.

Application filed May 27, 1885. Term of patent 3½ years.

To all whom it may concern:

Be it known that I, ALFRED ERNEST HILLS, a subject of the Queen of Great Britain, residing at 14th Waterloo Road, Burslem, in the 5 county of Stafford, England, have invented and produced a new and original Design for Vegetable-Dishes and other Table-Ware, of which the following is a specification, reference being had to the accompanying photographs, forming part thereof, in which—

Figure 1 is a view of a vegetable-dish and its cover made in accordance with my new design. Fig. 2 is a view of the dish, the cover being removed. Fig. 3 is a view of the cover.

15 My invention relates to a new configuration for a vegetable-dish or other china household article, such as a tureen, sauce-boat, pitcher, tea-pot, or sugar-dish.

The dish A is made in the form of an elongated hexagon, the two opposite sides *b b* being parallel, while the end portions are made angular, being each tapered in a horizontal plane from the points *c c* to the point *d*, as seen in Fig. 2. Each side of the dish is composed of a vertical or nearly vertical portion, *e*, united at *f* to a slightly convex lower portion, *g*, extending downward and inward to the curtain *h*, which is provided at the center of each side with an offset or projection, *i*, 25 and at the six angles with outwardly-inclined feet *k*. At the pointed extremity *d* of each end is an ornamental angular handle, *m*.

The cover B is of hexagonal form with two parallel sides and two ends, each terminating 30 in a point corresponding in general outline to that of the body A of the dish, and having a

shoulder around its outer edge and six angular faces, *n*, with a convex curvature, the lines of intersection of the faces extending from the six corners of the cover to the flattened hexagonal top *p* of the same, which is surmounted by an angular flattened handle, *q*, having an ornamental raised design on each side, the top of the handle sloping upward from each end to the center or apex, as shown in Fig. 1.

45

What I claim as my invention, and desire to secure by Letters Patent, is—

1. The design for a hexagonal dish having two parallel sides, *b b*, and two angular end portions, each tapered or inclined horizontally 50 in a straight line from the points *c c* to the point *d*, where they unite and form an angle, the said sides and ends consisting of a vertical or nearly vertical upper portion, *e*, having handles *m*, and a convex lower portion, *g*, extending downward and inward from the portion *e* to the bottom, and having feet *k* at the angles, substantially as herein shown and described.

2. The design for the hexagonal dish-cover 60 B of the outline shape shown, having six angular convex faces, *n*, extending upward from the lower edges, and having a flat hexagonal top, *p*, surmounted by an ornamental handle, *q*, substantially as herein shown and described.

65 Witness my hand this 28th day of April, A. D. 1885.

ALFRED ERNEST HILLS.

In presence of—

SAMUEL FORD,

GEORGE CHRISTOPHER GUEST.
